His Attorney.

UNITED STATES PATENT OFFICE

HENRY E. BUTLER, OF SCOTIA, NEW YORK, ASSIGNOR TO GENERAL ELECTRIC COMPANY, A CORPORATION OF NEW YORK

FILM CUT-OUT

Application filed June 12, 1929. Serial No. 370,209.

The present invention relates to circuit controllers of the type usually termed "film cutouts" and especially to film cutouts of the disc type. Film cutouts of the disc type are used extensively in connection with series lighting circuits and the manner of their use is well-understood by those familiar with such lighting circuits. The arrangement employed usually is well-illustrated in the 10 patent to Howell 717,201, dated December 30, 1902.

Disk film cutouts in common use comprise two plates of thin metal between which is located a suitable insulating material, such 15 as thin paper, cloth or the like, the plates and insulating material being united by an insulating adhesive such as shellac, for example.

In manufacturing film cutouts of this 20 type, it is the practice to coat the insulating material with an adhesive and then place the coated material between the two plates, the adhesive serving to stick the parts together. With this arrangement, it has been found 25 that there is sometimes considerable variation in the dielectric strength of the insulation, this being due to the fact that the coating may be applied unevenly, or to the fact that in one instance the coating is thinner 30 than in another instance. As a result in some cases, the film will rupture at too low a voltage while in other cases it will not rupture until the voltage reaches an undesirably high value. A uniform product which will 35 rupture always at the desired voltage is difficult to produce.

The difficulties above referred to are especially noticeable in connection with the manufacture of disc film cutouts for low 40 voltage circuits, it being especially difficult to obtain a uniform product which will operate reliably on low voltage series circuits.

One object of my present invention is to provide an improved construction of disc 45 film cutout which will enable the cutout to be manufactured readily and at the same time provide cutouts having uniform break-down potentials.

A further object of my invention is to provide a disc type film cutout which can be

manufactured with accuracy for any desired breakdown voltage, it being adapted to be made for low voltage circuits as well as for relatively high voltage circuits.

According to my invention, I form my improved film cutout from two metal pieces, separated by a film of insulating material, but instead of uniting the parts by an adhesive as heretofore, I altogether dispense with the use of an adhesive and instead unite the two pieces mechanically through the intermediary of an insulating disc, the use of an insulating disc possessing special advantages as pointed out hereinafter.

In the drawing, Fig. 1 is side elevational view on an enlarged scale of a cutout embodying my invention, applied to a series incandescent lamp holder, said holder being shown in section; Fig. 2 is a central sectional view of the assembled cutout; and Fig. 3 is an exploded sectional view of the parts which form the cutout. Figs. 2 and 3 are drawn on a greatly enlarged scale in order better to illustrate the invention.

Referring to the drawing, 1 and 2 represent the usual contact arms of a series incandescent lamp receptacle, such as is in common use for incandescent street-lighting and between the extremities of which the film cutout is located.

Referring to Figs. 2 and 3, 3 and 4 indicate the two metal pieces of the cutout separated by the insulating film 5 which may be in the form of lacquer or the like sprayed over one or both of the pieces, or in the form of a separate piece of thin paper, cloth or the like, located between the two metal pieces. The metal piece 4 is of smaller diameter than the metal piece 3 and the two metal pieces are held in assembled relation relatively to each other with the insulating film between them by means of an insulating disc 6 formed of a material sufficiently stiff to enable it to hold the parts in their assembled relation. The metal piece 4 is provided with a projection 7 at its central portion which extends through an opening 8 in disc 6 and projects somewhat beyond the confines of the same. The insulating disc 6 may be fastened to metal disc 3 in any suitable manner. In the present in-

stance it is shown as being fastened to metal disc 3 by means of an inturned flange 9 at the peripheral edge of disc 3. The projection 7 extends beyond the plane of the outer surface of the inturned flange 9 so that when the cutout is positioned between the contact arms 1 and 2, the one contact arm engages only the projection 7. With this arrangement it will be seen that when the cutout is in position, as shown in Fig. 1, disc 3 is in contact with one arm and the projection 7 on disc 4 is in contact with the other arm, the two arms being then insulated from each other by the film 5.

15 The discs 3 and 4 may be formed with advantage from thin aluminum, although any other suitable conducting material may be used. The disc 6 may be formed of any suitable insulating material having the desired 20 degree of stiffness; for example, I may use varnished paper.

In constructing and assembling the cutout I may first form a cup-shaped piece, as shown at the left-hand side of Fig. 3. The dielectric film material 5 may be then placed in 25 this cup-shaped piece, the disc 4 placed on top of it, and then insulating disc 6 may be placed over the projection 7. After the parts are thus assembled the flange of the cup-shaped piece may be bent over, as shown in 30 Fig. 2, tightly clamping the film material 5 and the disc 6 in position, the disc 6 in turn holding the metal disc 4. With this arrangement it will be seen that the peripheral edges 35 of the metal discs 3 and 4 are well separated from each other so that there is no danger of their coming into contact accidentally. Since the holding disc 6 is formed of insulating material there is no possibility of short-circuiting the cutout when the flange of the 40 disc 3 is crimped over, as shown in Fig. 2. This is an important consideration as it means that it is unnecessary to take special care in the manufacture of the cutout.

45 By my invention, it will be seen that I am enabled to provide a film cutout comprising only two metal pieces, a dielectric film between them, and a spacing insulator the use of an adhesive being avoided. By this arrangement, I am enabled to select and provide a dielectric film material which is uniform in dielectric strength and which will puncture at the desired voltage value. As a result, I am enabled to provide film cutouts 50 which will in all cases be uniform in dielectric strength. This means that I am enabled to provide a uniform product for any desired voltage value.

What I claim as new and desire to secure 60 by Letters Patent of the United States, is:

1. A film cutout comprising a metal piece, a second metal piece having a centrally disposed struckout portion, an insulating film separating said pieces, an insulating member 65 which engages the second-named metal piece,

and a flange on the first named metal piece which overlies the insulating member to hold the metal pieces in fixed assembled relation.

2. A film cutout comprising a metal piece having engaging means, a metal piece having a centrally disposed struck-out portion, an insulator for separating said metal pieces, and an insulator having a centrally disposed perforation adapted to receive the struck-out portion of the second-named metal piece, 70 said second-named insulator co-operating with the engaging means of the first-named metal piece and with the second-named metal piece for holding said metal pieces in fixed 75 assembled relation.

3. A film cutout comprising two metal discs of different diameters, an insulating film separating said discs, an insulating disc engaging the metal disc of smaller diameter, and a flange on the metal disc of larger 80 diameter which clamps said insulating disc to hold the cutout assembled.

In witness whereof, I have hereunto set my hand this 11th day of June, 1929.
